CLAIM

The ornamental design for a housing for charging station for a wheeled battery-powered device, substantially as shown and described.

DESCRIPTION

FIG. 1 is a front, right side, and top perspective view thereof;
FIG. 2 is a right side elevation view thereof;
FIG. 3 is a left side elevation view thereof;
FIG. 4 is a front elevation view thereof;
FIG. 5 is a rear elevation view thereof;
FIG. 6 is a top view thereof; and,
FIG. 7 is a bottom view thereof.

The broken lines shown in the drawings are included for the purpose of illustrating portions of the article that form no part of the claimed design.

1 Claim, 4 Drawing Sheets
